PLANT FOR THE PRODUCTION OF OXYGEN

Plotr Tulacz, Pueyrredon 2010, Buenos Aires, Argentina

Filed Aug. 31, 1956, Ser. No. 607,314

5 Claims. (Cl. 62—37)

This invention relates to a plant for the production of oxygen and its final bottling.

The plant has been specially designed for putting advantageously in practice the process of producing oxygen by fractionating the main components of liquid air—namely, nitrogen and oxygen—with the elimination of the carbon dioxide and humidity also present in liquid air.

The new assembly constituting the plant of the invention is a combination of elements, some of them already known, others completely novel, assembled according to a certain functional order, placed and correlated so as to achieve an easy operation and to obtain and maintain the two main factors which determine the final results. These factors, pressure and temperature, are balanced so as to obtain the highest benefit by reciprocally increasing or decreasing one at the expense of the other; in this way, efficiency is combined with economy in production costs and high quality of the oxygen obtained.

From the strictly constructive point of view, the plant of the invention is constituted by the association of the following elements: means for the admission and filtration of air combined with a first compressor which compresses the air up to a certain pressure and delivers it to a second compressor, associated to the first one, wherein the pressure of the air rises to a higher level; the air so compressed passes through a carbon dioxide retaining device connected to a third compressor which compresses the air up to an even higher pressure. Directly following the third compressor, there is connected a drier coupled to a first heat exchanger continued by a pipe which divides into two branches; of these two branches, one is connected to a decompressor and to a second heat exchanger. The assembly includes a fractionating column, provided at its lower portion with a first coiled tube connected by one part of the branch passing through the second heat exchanger and, by the other part, to a first column feeding pipe. The other branch of the branched pipe is connected to a third heat exchanger and to the base of the said column, forming there a second coiled tube which, in its turn, is connected to a second feeding pipe of the fractionating column. At the upper part of the fractionating column there is connected a third pipe which passes through the three heat exchangers and, finally, discharges to the atmosphere. The assembly is completed by a conduit which, starting from the said column at the zone adjacent to the coils, passes through the third and first heat exchangers and is connected to a flow-control organ associated to a fourth compressor which is provided with means for bottling the oxygen into adequate recipients.

It must be remarked the important and novel fact that the decompressor and the third compressor have common crank and crankcase, thus being avoidable the usual brake because the drive of the decompressor is transmitted directly to the crank. This arrangement results in a great economy in compressive work and also reduces the construction costs.

2

It must be remarked also the particular construction and arrangement of the fractionating column which constitutes in itself one of the most important organs of the plant of the invention.

- 5 With respect of the fractionating elements or trays of the fractionating column, it must be remarked the importance of achieving, the same as in the case of a petroleum or alcohol rectifier, a maximum interchange between the liquid and gaseous phases in equilibrium.
- 10 With the usual dome or "calotte," even in the case when the trays have peripheral openings or are provided with a "comb—" shaped system of parallel teeth, the interchange between both liquid and gaseous phases is extremely brief, it being reduced to the very short lapse during which the vapor bubbles through the liquid covering the tray and sealing the edge of the dome. The case is similar with the Barber, Savalle and Ynillanme trays, though it must be reckoned that the Egrot tray is relatively more efficient in the case of rectifiers.
- 15 The multibored tray, such as used in the Savalle discontinuous rectifier, represents an important improvement, though the columns provided only with this type of fractionating element present the problem of their too much easy discharge through the bores when the flow is lesser than that foreseen, this effect taking place normally when the plant starts to operate or when the temperature suddenly decreases in a certain zone of the column, particularly when the temperature of the liquid fed into the column changes.
- 20 The present invention solves this important aspect of the nitrogen-oxygen fractionating process by employing combined and superposed double trays with devices such that provoke an intense circulation of the liquid in the lower tray, due to the effect of the issuing gases or vapors which impulse and circulate the said liquid and, simultaneously, multiply, by repetition, the lapse during which both phases are in contact, the said liquid finally dropping into the lower system as an overflowing foam through "trop-pleins" provided to such end.
- 25
- 30 The present invention solves this important aspect of the nitrogen-oxygen fractionating process by employing combined and superposed double trays with devices such that provoke an intense circulation of the liquid in the lower tray, due to the effect of the issuing gases or vapors which impulse and circulate the said liquid and, simultaneously, multiply, by repetition, the lapse during which both phases are in contact, the said liquid finally dropping into the lower system as an overflowing foam through "trop-pleins" provided to such end.
- 35
- 40 In its turn, the base of this tray offers, due to its concave shape, a large surface of the gases coming up from the complementary lower tray, this fact having an important thermal influence on the liquid contained in the said tray.
- 45 The complementary tray is placed upon the aforementioned tray and is provided with bores all over its surface and is provided also with trop-pleins for the discharge of liquid into the other tray, which will be called from now on as the "lower main tray." The interchange of phases and calories takes place due to the passage of gases through the several and small bores provided all over the surface of the upper element.
- 50 Discarding the effects of retrogradation from one tray to another and from one assembly to the immediate one, always present in fractionating columns, it is remarked, in the case of this invention, the sinuous path of the gas in its upward progress, since the gas strikes on the centre of the middle portion of the lower tray, is then diverted to the periphery, and from there passes, in a diffused way, to the upper unit, being directed there to the centre of the upper group.
- 55
- 60 The thorough, multiple and persistent interchange between the liquid and gaseous phases, and the rupture in the uniformity of the ascending flow, due to the sinuous direction of its path, result in an intense rectification or fractionation, the ascending nitrogen gases being extraordinarily enriched as they lose oxygen, and the latter, in its turn, progressively deprived of nitrogen as it falls or retrogrades as a liquid phase from one tray to another.
- 65
- 70 The chance of a probable discharge of the bored tray in the case of depressions produced by excessive condensation at certain zones is prevented and solved in the

present invention thanks to the presence of the lower tray of each group which is filled with liquid and, as the latter makes a water or hydraulic seal over the whole surface of the tray, the normal discharge path of the liquid is through the trop-pleins, thus being discarded the possibility of a direct communication between groups.

This is particularly important when the column starts to operate, because the distillation takes place at the desired rate and in a time shorter than that needed in the normal operation with uniform trays.

Equally remarkable among the organs constituting the plant of the invention is the organ for controlling the volume of liquid flowing into the compressor of the bottling machine.

The said organ, which will be called "stato-volume," tends to maintain a steady provision of oxygen for the compressor of the bottling machine, in order that under no circumstance the said compressor would draw directly from the circuit because in that case a harmful alteration in the pressure regimen at the intake zone and, consequently, in the fractionating column, takes place when the feeding rate of the bottling machine is greater than the production rate of the plant.

Up to the present there were not efficient and practical means for preventing this trouble. The present invention solves this problem in a novel and satisfactory way by the employment of a rubber bag placed inside a metallic tank, the upper portion of the said bag being connected by means of two fixed pipes to the intake of the compressor and to the circuit carrying pure oxygen. A relatively heavy body rests on the upper portion of the bag and has arms for the command of an electric switch constituted by a cell partially filled with mercury.

The cell has two electric wires connected to the electric circuit operating the compressor and placed in such way that, when the bag is empty, the cell adopts, as an effect of the movement of the arms, a position in which the mercury covers only one of the electric wires, at most. When the bag is almost filled the cell adopts a position in which the mercury covers both wires, thus closing the electric circuit which operates the compressor which is drawing the oxygen out of the bag and impulsing it into the bottle. A similar performance would be achieved by means of an electromagnetic valve operating the intake valve of the compressor.

Two stop members, placed on the upper arm, determine, due to their complementary action on a forked lever operating on a switch, the moment at which the circuit is closed or opened.

It is particularly important, due to its novel characteristics, the controllable air decompressor which tends to produce a decompression in the pre-cooled air so as to obtain, by expansion, a better cooling effect. To maintain the required air temperature and pressure rates after the decompression implies the compensation of the variations in the system due to the fluctuating thermal conditions of the external air fed into the circuit.

The preceding aim has been frequently approached by applying variable resistances in the electric circuit, by braking the motor, etc., in order to regulate the number of revolutions per minute of the decompressor; thus resulting in the latter an increased or decreased number of strokes per minute.

The present invention offers a novel, efficient and practical solution of the problem presented by the fluctuating air conditions.

This solution is based on the existing correlation between the fall in the air temperature, which is the phenomenon desired, and the air pressures before and after the said fall of temperature, due to the decompression of the volume of air introduced into the cylinder of the decompressor. This is achieved by modifying the volume of the air effectively introduced by regulating the moment of closing the intake valve of the decompressor in rela-

tion to the moment when the piston is at the top dead center and, correlative, by regulating the moment of opening the exhaust valve. To a greater retard in closing the admission, corresponds a greater volume of intake air. In its turn, the greater is the volume of the air introduced, the greater is, for the same cylinder capacity, the cooling effect and correlative.

In the case of the plant for the production of oxygen which is the object of this invention, the regimen must be obtained by means of a decompression from 40 to 5 atmospheres, these being the normal pressures before and after the said decompression.

In the accompanying drawings:

Fig. 1 represents schematically the plant for the production of oxygen and its final bottling.

Fig. 2 illustrates a vertical cross-section of the fractionating column, showing the constructive details of the component trays.

Figs. 3 and 4 are top views showing the characteristics of the elements constituting the column.

Figs. 5, 6 and 7, represent, respectively, two lateral and a top view of the organs for controlling the volume of oxygen flowing into the compressor of the bottling machine. Fig. 5 is taken along line of A—A of Fig. 7 and Fig. 6 is taken along line B—B of Fig. 7.

Figs. 8 and 9 represent different aspects of the decompressor regulating device, Fig. 10 being a variant of the same device.

According to what is illustrated in Fig. 1, the plant of the invention comprises means, related to compressors 2 and 3, for the admission and filtering of the air, the first and second compression stages taking place inside those compressors.

The column 4 is a carbon dioxide retaining device containing sodium dioxide. 5 and 6 correspond, respectively, to the cylinder wherein the third compression takes place and to the adsorptive air drier.

7 and 12 are heat exchangers. The device 10 is the air decompressor, 13 representing the fractionating column provided with fractionating double trays 22. Finally, 27 is a compressor for bottling the oxygen into the tube 29, being provided the "stato-volume" 28 as an intermediate feeder.

The operation of the plant is as follows:

The air, filtered at 1, is first compressed up to 3 atmospheres (about 45 pounds per square inch) in the compressor 2, then passes to the compressor 3 wherein its pressure is increased up to 12 atmospheres (about 180 pounds). The air then ascends through the column 4, leaving there its carbon dioxide content, and then passes to the compressor 5 wherein is compressed for the third time up to a pressure of 40-42 atmospheres (about 600 pounds).

Then, the air descends through the drier 6 and ascends through the heat exchanger 7, where its temperature is reduced to 90° C. below zero, and through the pipe 9 branched off in two pipes, 15 and 15a. The branch 15 carries off the larger amount of air, and is connected to the decompressor 10 wherein the said air expands while its pressure is reduced down to 4 or 5 atmospheres (about 60-70 pounds), and due to this decompression the temperature of the air is lowered to 150° C. below zero. From there, the air flows through the pipe 11 into the heat exchanger 12 wherein its temperature drops to 175° C. below zero due to the refrigerating effect of the very cool nitrogen coming, as it will be explained later on, from the column 13, and ascending through the said heat exchanger.

The semi-liquified air flows inside the cooling coil 14, at the base of the fractionating column 13, the said coil being submerged in a bath of oxygen at 185° C. below zero. The air, completely liquified in the said coil, flows through the throttle valve 21, and enters the fractionating tower or column 13, at the upper portion of the latter.

The other branch 15a derived from the pipe 9 is connected to the heat exchanger 16. The air flowing inside it is cooled down to 142° C. below zero due to the combined effect of the counter-current refrigeration by the oxygen flowing inside a coil and of the nitrogen fed through the pipe 17 and diffused inside the said heat exchanger. The said air flows inside the pipe 18 and enters the fractionating column at the base, wherein it is cooled and liquified as it passes through a coil, and is fed from above into the fractionating column 13 after passing through the pipe 19 and the throttle valve 20.

The fractionating column, 13, partially represented in Fig. 2, is constituted by a series of superposed trays 22, particularly illustrated in Figs. 2, 3 and 4 (22 and 22a).

The tray 22 is constituted by a disc 30 whose periphery abuts against the wall of the column 13. The said disc is provided with regularly spaced bores 38 of 2 millimeters in diameter. The tubular "trop-pleins" 31 overtop the trays up to a certain height corresponding to the level the liquid should reach when covering the tray, the said tray offering a metallic concavity 32 which makes easier the discharge of the exceeding liquid towards the main trop-plein 33 in the lower or main tray 22a. This lower or main tray consists of a container whose circumferential periphery coincides and is adjusted to the wall of the column 13, the said container being constituted by a plate with a concave bottom at its central zone, a straight portion 35 inclined towards the periphery 36, and a circular recess 37 at the centre of the tray, this recess limiting the storage capacity of the tray.

The tube 33, provided with a funnel 39, a fold 40 and a flange 41, rests on the central recess 37 of the tray, its flange 41 offering a bearing edge for the annular plate 42, whose surface is corrugated at sharp angles, the said plate being placed as an inverted shell with a central opening 43. The corrugated annular plate 42 rests along its periphery on the lower tray, and maintains a certain clearance with respect to the wall of the periphery 36 of the said tray.

The lower end of the trop-plein 33 is inserted into the concavity 32 of the bored tray which, together with another unit 22a, constitutes another double tray of the plurality of similar assemblies constituting the fractionating column 13.

Generally speaking, the process inside the fractionating column is as follows:

The liquid air drops from one tray into another while being submitted to the countercurrent of vapors or gases, particularly rich in nitrogen, issued as the liquid air descends the column, pure oxygen being thus obtained, finally, at the base of the column. The nitrogen, as a gaseous phase, is progressively deprived of oxygen as it mounts the tower or column and, at the end of this process comes out with a 10% content of oxygen. This nitrogen is taken by the pipe 23 and carried through the heat exchangers 12, 16 and 7, being finally delivered to the atmosphere after passing through the regulating valve 25.

The gaseous oxygen separated by effect of the heat exchanged at the coils 14 and 18 at the base of the column comes out from 24 as a saturated gas, passes through the heat exchangers 16 and 7 and through the valve 26, and flows then to the compressor 27, after passing through the stato-volume 28, being finally bottled into the tube 29.

Particularly considered, the operation inside each combined tray 22 and 22a is as follows (Fig. 2):

The sinuous line 45 and the branches derived from it represent the ascendent path of the gases through one section of the column, and the lines 46 represent the flow of the liquid phase as it overflows and drops into the lower combined tray. The line 47 illustrates the firm recirculation of clean liquid under the pressure of the gases. This process is reproduced in an identical way in each one of the sections or corrugations of the annular

plate 42, thus putting into evidence the intense exchange between the liquid-gaseous phases of the oxygen-nitrogen as the oxygen descends the column and is progressively purified.

5 In this way, due to the novel characteristics of the fractionating column and the intense exchange obtained in its double trays, it is possible to obtain an oxygen of maximum purity with a minimum of trays.

10 In Figs. 5, 6 and 7, the organ for controlling the volume of oxygen drawn in by the compressor of the bottling assembly is represented in detail.

This controlling organ, which has been referred to in this description as the "stato-volume," is constituted by a metallic box 48 provided with a lid 58, inside of which there is placed a rubber bag 49.

A heavy body 53 rests upon the upper portion of the said bag, the said body having a metallic arm 59 rotatably mounted at 52, between the pipes 50 and 51, or at other fixed portion such as the lid 58.

20 A second metallic arm 54, of an easy-curved shape, is fixed to the body 53, forming an angle of about 90° with respect to the arm 59, passes freely through the opening 60 in the lid 58, and ends at 61.

The arm 54 operates the cell of a mercury electric switch 57.

25 It is a characteristic of the invention the fact that two stop members, put at a certain distance at the upper part of the arm 54, act upon a forked member operating in an electrical switch placed so as to cause the operation of the said forked member as the arm 54 moves upwards or downwards, the said switch and forked member being fixed to a point independent of the said arm.

The stato-volume operates in the following way:

30 The bag 49 being empty and the cell being at the position shown in Fig. 6, the compression does not take place due to the fact that the electric circuit remains open as long as the mercury is accumulated at one end of the cell. The gaseous oxygen flows into the bag through the pipe 50, under the effect of the gas pressure inside

35 the piping system of the plant. As the bag 49 gets filled with oxygen, the said cell tends to adopt a horizontal position up to the point where the mercury touches both ends of the cell and thus closes the electric circuit; at this very moment, the compressor 27 starts to operate, Fig. 1, continuously drawing in oxygen through the pipe 51 and compressing it into the tube or bottle 29 (Fig. 1) until the bag is emptied; at this moment the electric switch is opened and, consequently, the compressor stops.

40 The application of the electric switch and its corresponding fork, not represented in the drawings, makes possible to regulate the opening of the circuit at any determined position of the arm 54.

45 The controllable decompressor 10, Figs. 8 and 9, is constituted by a plunger 61 pushed by a connecting rod of the corresponding compressor running at a fixed number of revolutions per minute, the cylinder 62 being sealed by means of the packings 63, 64 and 65, the intake and exhaust valves being respectively operated by the levers 66 and 67, the cams 68 and 69 being moved, in 50 their turn, by the camshaft 70.

The said camshaft and the cams have an elongated helicoidal key 71 mounted in a groove of similar shape formed in the said camshaft.

55 The fork 75 embraces both cams and is apt to be moved along the camshaft due to the action of a worm 78 supported by bearings 77 fixed to the base of the housing, the said worm being operated by the crank 79.

The operation is as follows:

60 If the volume of the intake air is to be reduced, the fork 75 and, consequently, the cams 68 and 69 must move along the camshaft impulse by the crank 79 and worm 78 mechanism; the displacement of the fork produces, due to the helicoidal key 71, a revolving movement of the cam with respect to the camshaft, and the resulting angle 75 of rotation determines the moment when the cam oper-

ates upon the intake valve, in relation to the intake stroke of the plunger whose driving axle is synchronized with the camshaft, as usual.

In the present invention, the air normally fed into the decompressor is at 40 atmospheres and must be decompressed down to 5 atmospheres and 150° C. below zero, these being the normal operating conditions of the rest of the plant. The external air temperature variations particularly affect the pressure and temperature of the air fed into the decompressor. In the case of this invention, the regulation of these conditions can be achieved even when the plant is fully operating.

It has been also foreseen the independent application of the device of the invention to each cam, in order to adjust the closing of the intake valve independently from the opening of the exhaust valve.

Another solution of this important problem is that illustrated in Fig. 10.

The camshaft 70 has a pinion 74, and there is provided another pinion 72 fixed to the compressor camshaft, both pinions being engaged by the chain 73. A lever 81, operating on the camshaft 70, has an adjustable and movable pinion 80, also engaged to the chain 73. Finally, there is a tension pinion 82 also engaging the said chain.

The operation of this latter device is as follows:

If, when the camshaft and the compressor crankshaft are normally synchronized, the pinion 80 is displaced by means of the lever 81 so that the chain engages the pinion 74 along an increased circumferential length corresponding to the angle b , a similar but opposed and diminished effect takes place at the crankshaft pinion. The relative movement of the camshaft with respect to the pinion of the crankshaft is thus retarded, this retard being transmitted to the opening and closing operation of the valves.

Having described the invention and the way of its practical execution, it is claimed as exclusive property and right:

1. In an apparatus for producing oxygen from air by at least partial liquefaction of said air and fractionation thereof at predetermined pressure in a fractionating vessel, in combination, movable compressor means for compressing air to be liquefied; expander means for expanding a controlled portion of said compressed air, said expander means being connected to said compressor means for joint movement; adjustable control means for controlling the amount of air to be expanded in said expander means during movement thereof with said compressor means; conduits for respectively feeding said expanded portion of said compressed air and the remaining portion thereof in unexpanded condition to said fractionating vessel; withdrawing means for withdrawing oxygen from said fractionating vessel through a discharge conduit and including a collapsible storage means sensitive to the pressure in said conduit; and pressure responsive control means responsive to pressure variation in said discharge conduit for controlling the rate of withdrawal of said oxygen from said fractionating vessel and including actuating means associated with said storage means for actuating operation of said withdrawing means so as to actuate said withdrawing means when said storage means is in the non-collapsed condition and stopping operation of said withdrawing means when said storage means is in a collapsed condition, whereby the pressure in said fractionating vessel is maintained at a predetermined value.

2. In an apparatus for producing oxygen from air by at least partial liquefaction of said air and fractionation thereof at predetermined pressure in a fractionating vessel, in combination, movable compressor means for compressing air to be liquefied; expander means for expanding a controlled portion of said compressed air, said expander means being connected to said compressor means for joint movement; adjustable control means for controlling the amount of air to be expanded in said expander means during movement thereof with said com-

pressor means; conduits for respectively feeding said expanded portion of said compressed air and the remaining portion thereof in unexpanded condition to said fractionating vessel; withdrawing means for withdrawing oxygen

- 5 from said fractionating vessel through a discharge conduit and including a collapsible storage means sensitive to the pressure in said conduit; and pressure responsive control means responsive to pressure variation in said discharge conduit for controlling the rate of withdrawal of said oxygen from said fractionating vessel and including actuating means associated with said storage means for actuating operation of said withdrawing means so as to actuate said withdrawing means when said storage means is in the non-collapsed condition and stopping operation of said withdrawing means when said storage means is in a collapsed condition, said actuating means comprising a liquid switch of the type that the switch is in the on position when the liquid in the switch touches two contacts at opposite ends of a level-like container, 10 said switch being associated with the top of said collapsible storage means, thereby actuating said withdrawing means when said storage means is substantially full and the switch is level, and stopping the operation of said withdrawing means when said storage means have collapsed sufficiently for the relative level position of the switch to have shifted so that the switch liquid no longer covers the contacts, whereby the pressure in said fractionating vessel is maintained at a predetermined value.
3. In an apparatus for producing oxygen from air by 15 at least partial liquefaction of said air and fractionation thereof at predetermined pressure in a fractionating vessel, in combination, movable compressor means for compressing air to be liquefied; expander means for expanding a controlled portion of said compressed air, said expander means being connected to said compressor means for joint movement; adjustable control means for controlling the amount of air to be expanded in said expander means during movement thereof with said compressor means, including intake and output valve means 20 and actuating means for actuating the opening and closing of said valve means in a predetermined time cycle in unison with movement of said expander means and including a pair of eccentric cams, one of said cams being designed to operate the intake valve means of said expander means, the other of said cams being designed to operate the output valve means of said expander means, a camshaft synchronously movable with said expander means on which camshaft said cams are mounted, and manual means to vary the angular position of said cams on said shaft, whereby the relative position of the expander means and the respective valve means is varied; conduits for respectively feeding said expanded portion of said compressed air and the remaining portion thereof in unexpanded condition to said fractionating vessel; withdrawing means for withdrawing oxygen from said fractionating vessel through a discharge conduit; and pressure responsive control means responsive to pressure variation in said discharge conduit for controlling the rate of withdrawal of said oxygen from said fractionating vessel, whereby the pressure in said fractionating vessel is maintained at a predetermined value.

4. In an apparatus for producing oxygen from air by at least partial liquefaction of said air and fractionation thereof at predetermined pressure in a fractionating vessel, in combination, movable compressor means for compressing air to be liquefied; expander means for expanding a controlled portion of said compressed air, said expander means being connected to said compressor means for joint movement; adjustable control means for controlling the amount of air to be expanded in said expander means during movement thereof with said compressor means, including intake and output valve means, actuating means for actuating the opening and closing of said valve means in a predetermined time cycle in unison with movement of said expander means, a pair of eccentric cams, one of

said cams being designed to operate the intake valve means of said expander means, the other of said cams being designed to operate the output valve means of said expander means, a camshaft synchronously movable with said expander means on which camshaft said cams are mounted, a helical key on said camshaft engaging said cams, holding means holding said cams in a predetermined relationship, and a manually rotatable worm, the rotation of which moves said holding means and therefore said cams along the camshaft, the angular position of said cams relative to said camshaft being varied by said helical key while said cams move along said camshaft, whereby the relative position of the expander means and the respective valve means is varied; conduits for respectively feeding said expanded portion of said compressed air and the remaining portion thereof in unexpanded condition to a said fractionating vessel; withdrawing means for withdrawing oxygen from said fractionating vessel through a discharge conduit; and pressure responsive control means responsive to pressure variation in said discharge conduit for controlling the rate of withdrawal of said oxygen from said fractionating vessel, whereby the pressure in said fractionating vessel is maintained at a predetermined value.

5. In an apparatus for producing oxygen from air by at least partial liquefaction of said air and fractionation thereof at predetermined pressure in a fractionating vessel, in combination, movable compressor means for compressing air to be liquefied; expander means for expanding a controlled portion of said compressed air, said 25 expander means being connected to said compressor means for joint movement; adjustable control means for controlling the amount of air to be expanded in said expander means during movement thereof with said compressor means, including intake and output valve means, actuating means for actuating the opening and closing of said valve means in a predetermined time cycle in unison with movement of said expander means, a pair of eccentric cams, one of said cams being designed to oper-

ate the intake valve means of said expander means, the other of said cams being designed to operate the output valve means of said expander means; a camshaft synchronously movable with said expander means on which 5 camshaft said cams are mounted, rotary driving means for driving said expander means, a sprocket and chain arrangement connecting said cams to said driving means for synchronous operation, said chain having a tight and a slack strand, and an adjustable sprocket acting on said 10 chain to vary the relative lengths of said tight and slack strands so that the relative angular position of said cams and said drive means during synchronous movement thereof may be controlled; conduits for respectively feeding said expanding portion of said compressed air and 15 the remaining portion thereof in unexpanded condition to a said fractionating vessel; withdrawing means for withdrawing oxygen from said fractionating vessel through a discharge conduit, and pressure responsive control means responsive to pressure variation in said discharge 20 conduit for controlling the rate of withdrawal of said oxygen from said fractionating vessel, whereby the pressure in said fractionating vessel is maintained at a predetermined value.
